UNITED STATES PATENT OFFICE.

JOSEPH BABICZKY, OF KANSAS CITY, MISSOURI.

FIREPROOF BUILDING CONSTRUCTION.

SPECIFICATION forming part of Letters Patent No. 780,700, dated January 24, 1905.

Application filed October 29, 1903. Serial No. 179,098.

To all whom it may concern:

Be it known that I, JOSEPH BABICZKY, a citizen of the United States, residing at Kansas City, in the county of Jackson and State of Missouri, have invented certain new and useful Improvements in Fireproof Building Constructions; and I do declare the following to be a full, clear, and exact description of the invention, such as will enable others skilled in the art to which it appertains to make and use the same.

My invention is an improved hollow fireproof structure comprising a supporting frame having double foraminated metallic walls spaced apart and forming the sides of the frame and a plastic filling in the space or spaces between the said double walls, said filling projecting through the openings in the metal walls and being smoothed to form a coating on the exterior surface of the outer walls, as hereinafter described and claimed.

In the accompanying drawings, Figure 1 is a vertical sectional view through a double wall or partition embodying my invention. Fig. 2 is a similar view through a chimney or tubular structure constructed in accordance with my invention.

In the form of my invention shown in Fig. 1 the studs or boards 8 are connected together by horizontal laths or cross-bars 7, which are secured thereto and spaced a suitable distance in from their outer edges. The inner walls 9 are of foraminous metallic material, here shown as expanded metal sheets, and the same are secured to the said laths or cross-bars. The outer walls 10, which are appropriately spaced from the inner walls 9, are also of foraminous metallic material similar to that of which the inner walls 9 are composed, and said outer walls are secured to the outer edges of the said studs or boards 8. A plastic filling 5—such as beaten, concrete, or cement—is packed in the spaces between the double walls 9 10 and projects through the openings therein and is smoothed to form a coating on the exterior surfaces of the outer walls.

In Fig. 2 my invention is shown in the form of a chimney or tubular structure in which the frame is composed of inner and outer foraminous metallic walls 25 26, respectively, and 50 circular bands 24, which are suitably spaced apart and to which the inner and outer walls are secured. A filling 6, such as hereinbefore described, is packed in the spaces between the inner and outer walls and finished as herein- 55 before described.

The construction and advantages of my invention will be readily understood from the foregoing description, taken in connection with the accompanying drawings. It will be 60 seen that by using the expanded metal in the manner described the same serves as a mold and becomes a permanent part of the structure to add strength to the same. The need of temporary molds or scaffolding is thus obvi- 65 ated, and the structure may be erected very rapidly and possesses great strength and durability.

Various changes in the form, proportion, and the minor details of construction may be 70 resorted to without departing from the principle or sacrificing any of the advantages of this invention.

Having thus described my invention, what I claim, and desire to secure by Letters Patent, is—

A hollow fireproof structure comprising a supporting skeleton frame having doubled foraminated metallic walls spaced apart and forming the sides of the frame, and a plastic filling in the spaces between the said doubled walls, said filling projecting through the openings in the metal walls and being smoothed to form a coating on the exterior surfaces of the outer walls.

In testimony whereof I have hereunto set my hand in presence of two subscribing witnesses.

JOSEPH BABICZKY.
